UNITED STATES PATENT OFFICE

168,937

CHECKERBOARD

Blanche L. Hulcher, Virden, Ill.

Application April 17, 1952, Serial No. 19,366

Term of patent 14 years

(Cl. D34—5)

To all whom it may concern:

Be it known that I, Blanche L. Hulcher, a citizen of the United States and a resident of the city of Virden, county of Macoupin, and State of Illinois, have invented a new, original, and ornamental Design for a Checker Board, of which the following is the specification, and reference being had to the accompanying drawing forming a part thereof. In the drawing:

Fig. 1 is a top view of a checker board showing my new design.

Fig. 2 is a side view of the same.

The essential features of my design are shown in full lines.

I claim:

The ornamental design for a checker board, as shown and described.

BLANCHE L. HULCHER.
